[57] CLAIM

The ornamental design for an endometrial cell sampler,
as shown and described.

DESCRIPTION

FIG. 1 is a perspective view of an endometrial cell sampler showing my new design;

FIG. 2 is a perspective view thereof in disassembled
condition;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and

FIG. 8 is a bottom plan view thereof.

FIG. 1

FIG. 2

FIG.3

FIG.4

FIG.5 FIG.6

FIG. 7

FIG. 8
